COSMETIC CASE

Charles Gemora, Los Angeles, Calif.
Application April 16, 1954, Serial No. 30,049

Term of patent 14 years

(Cl. D86—10)

Fig. 1.

Fig. 2.

Fig. 3.

Fig. 4.

Fig. 5.

To all whom it may concern:

Be it known that I, Charles Gemora, a citizen of the United States, residing at Los Angeles, in the county of Los Angeles, State of California, have invented a new, original, and ornamental Design for a Cosmetic Case, of which the following is a specification, reference being had to the accompanying drawings, forming a part hereof.

Fig. 2 is a side elevational view thereof;

Fig. 3 is a rear elevational view thereof;

Fig. 4 is a front elevational view thereof; and

Fig. 5 is a perspective view thereof showing the case in open position and illustrating the interior thereof.

I claim:

The ornamental design for a cosmetic case, as shown.
